UNITED STATES PATENT OFFICE.

WILLIAM CORLISS, OF PROVIDENCE, RHODE ISLAND.

SAFE OR VAULT.

SPECIFICATION forming part of Letters Patent No. 447,488, dated March 3, 1891.

Application filed June 6, 1890. Serial No. 354,464. (No model.)

To all whom it may concern:

Be it known that I, WILLIAM CORLISS, of Providence, in the county of Providence and State of Rhode Island, have invented a certain new and useful Improvement in Safes or Vaults, of which the following is a specification.

The improvement relates to the means for securing the door, and for making a practically impermeable joint between the door and the door-casing.

I have in Letters Patent to me, dated June 26, 1883, No. 280,294, set forth a mode of making a joint and of securing the door, which 15 consists in providing stout plates, one for each of the four sides of the door, and moving these plates outward and inward, causing them to lap across the space between the door and the door-frame at a proper depth in the 20 material and tightly close the joint when the door is to be secured, and to be withdrawn when required and leave the door free to be opened and closed. In that patent the plates were withdrawn outward into the door-frame; 25 and when the door was to be secured the plates were moved inward across the joint and engaged in a groove in the door. Such arrangement necessitated the mounting of the machinery for operating the plates in the stationary parts of the safe or vault.

I have now devised an arrangement whereby the plates may be mounted in the door and withdrawn inward toward the center of the door. When the door is closed and it is 35 desired to lock it and to secure the joint, the plates are moved outward. The movement of the plates outward does not open any spaces at the corners, because I provide at each corner an obliquely-movable wedge-formed piece, which is arranged to move inward and outward. When the door is to be 40 locked, the plates which secure the main portion of the joint along each side and the top and bottom are thrown outward to the required small extent, and the obliquely-moving pieces are thrown outward in the corners to the required larger extent and close the apertures which would otherwise there exist. In unlocking the reverse takes place. The corner- 45 pieces move inward to the required large extent and the several edge plates are moved inward to their proper small extent. I pro-

vide connections so that these motions are induced by a single movement, the partial turning of a shaft which may be secured by a lock. 55

I have devised an improved construction of the eye or connection of the toggles to the plates, which gives a bearing over the whole thickness of the plate, and is eminently adapted to the application of great force if 60 such shall be necessary in urging the plates fully out.

The accompanying drawings form a part of this specification and represent what I consider the best means of carrying out the invention. 65

Figure 1 is a horizontal section through the door and the adjacent parts, omitting the operating mechanism. Fig. 2 is on a larger scale. It is a front view of the mechanism in 70 the left-hand upper corner of the door. This shows the mechanism with the locking-plates and the corner-piece forced outward into the recess in the fixed jamb or casing. Fig. 3 is a corresponding view of the same parts, showing the condition when the plates and corner-piece are withdrawn. Fig. 4 is a perspective view aiding to show the construction at the corner. Fig. 5 is a modification. It is a front view of the mechanism of the upper 75 portion of the door.

Similar letters of reference indicate corresponding parts in all the figures.

A are walls of brick or other suitable fire-proof material, having an air-space *a*, which 85 contributes to prevent the conduction of heat from the exterior inward in case of fire.

B is a door-casing of cast metal, having a groove *b* extending quite around.

D is a door of steel or other suitable material. It may be of any suitable construction which will give room for the plates and corner-pieces, and also room for the several levers and links required to give the proper motions of these important parts. 90

E are four movable plates of steel mounted in the door and extending along its four edges. They are adapted to move to a limited extent outward and inward. Each is provided with a transverse slot *e*, which receives 100 a pin fixed in the door, which keeps the plate in the correct position as it moves outward and inward.

Referring to the upper left-hand corner of

the door, G and H are links, hinged together at F, the link G turning on a fixed pivot D' set in the door and the link H turning on a circular head H', fitted in a corresponding recess in the plate E. By changing the angular position of these toggle-links G H the plates E are forced outward or drawn inward, as required. The pivot D' is set in such position in the door that it serves as a center for two levers G, one serving with its proper link H to move the horizontal plate E at the upper edge of the door and the other serving with the proper link for operating the vertical plate which serves on a vertical edge or side of the door. These two links G are in fact formed in one stiffly-connected part, and in addition to their functions as members of their respective toggles to force outward and draw inward their respective plates E serve also as a lever to communicate motion from the top to the side.

P is a wheel capable of being turned nearly a half-revolution by a suitable shaft and connection from the exterior of the door. (Not shown.) A pin P', carried on this wheel, communicates motion through a link O, which extends upward nearly to the top of the door, the upper end being guided by a pin or short arm O', traversing in a vertical groove d formed in the door. This pin O' connects by a link N with the center F. The turning of the wheel P a little less than a half-revolution by thrusting the link O forces the pivot F to the left, and by its direct effect through the first toggle G H raises the plate E at the upper edge of the door. The motion being communicated through the rigid connection of the two links or levers G together, correspondingly straightens the second toggle G H and moves outward the plate E at the side of the door.

I I are corner-pieces adapted to fill the wedge-formed spaces which exist between the beveled and grooved ends of the plates E at each corner of the door. These pieces I are tongued and move outward and inward between the adjacent plates E, respectively, in the grooves of which plates the tongues on the edges of the corner-pieces I are engaged. Their outer ends are properly formed to match in the groove b and to tightly close the joint between the door and the casing at the corner at those points. These pieces I have extensions I', each provided with a slot i', which receives the corresponding pivot D' and is guided thereby. To the extreme end of this extension I' is pivoted by a short link J a bell-crank lever K, turning on a center D², fixed in the door. A link L connects the other extremity with the center pin or knuckle F of the toggle G H.

The several plates E are beveled or reduced in thickness at their outer edges, and the groove b, in which they engage, is correspondingly beveled. When the plates E and the corner-pieces I are forced outward by the action of my mechanism, the movement not only

locks the door very effectually, but also draws it tightly to its bearing on the proper face of the casing and makes a tight joint. Furthermore, the plates E and the corner-pieces I, by their tight matching together at the corners and their tight matching into the groove along the entire length of the joint, form an additional bar to prevent the passage of flame when the safe is exposed to fire, or to prevent the entrance of water when the safe shall be drenched or immersed.

The revolving wheel P is secured by a lock M or other reliable fastening, or by a number of such locks, one of which may be a time-lock. When it is desired to open the safe, the wheel P is liberated by the action of the proper key or keys or by the action of the time mechanism, or both, and a proper force being applied through a shaft from the exterior or other means not shown the wheel P is partially revolved. Directing attention to the upper part of the safe, this partial revolution brings the pin P', which is connected with that portion of the mechanism, into the lowest position. This movement draws down the link O and draws on the link N, thus throwing the toggle-links G H into the inclined position shown in Fig. 3 and drawing inward the plate E, which extends across the upper edge of the door. The same movement by the rigid connection of the links G G into a bell-crank lever insures a corresponding action in the toggle G H, which controls the side plate E, and that is consequently drawn inward. The motion transmitted from the lower arm G through the link L to the lever K rocks this latter lever on its axis D² and through the link J draws the corner-piece I inward toward the center of the door. The proportions of the parts are such that this movement of the corner-piece I is much greater than that of the plates E. I have in my experiments made the corner-pieces I move outward and inward about three inches, while the plates E move outward and inward only about half an inch. This, through the wedge form of the corner-pieces I, provides a sufficient space at the several corners for the plates E to draw inward properly. When the safe is to be locked, a half-revolution of the wheel P in the opposite direction carries the link O upward, thereby bringing the links N into the level position and acting togglewise through these links on the toggles G H and causing the plates E to be strongly forced out. The same movement exerts a thrusting force through the links L and J and thrusts the corner-piece I I' outward to the large extent required to take up the increased space offered at the corners by the movement of the plates E E outward and make a tight joint at each corner of the safe.

The mechanisms at the several corners of the door are counterparts of each other. All are operated by a single half-revolution of the central wheel P.

The mechanism in the upper right-hand

- corner (not shown) is operated by a connection corresponding to the link N, connected to the rod O at the point O'. In other words, the rod O O' in being moved upward and downward operates two links N, extending in opposite directions from the pivot O', one of which operates the mechanism on the left-hand upper corner, as shown, and the other operates mechanism which is the exact reverse 10 thereof on the right-hand upper corner. (Not shown.)
- A pin corresponding to P' set in the wheel P opposite to the pin shown operates a link (partly shown) corresponding to O O', extending downward, and this latter guided the same as the rod O above operates by two links extending therefrom the mechanisms in the right and left corners respectively at the bottom.
- 20 I attach importance to the connection of the links H to the plates E by the circular heads H', applied in corresponding circular recesses in the plates. The heads H' are cylindrical, the axis of the cylinder lying at right angles 25 to the direction of the link. The diameter of the head is considerably larger than the breadth of the neck, or of that part of the link adjacent to the head, and which, with the play of the mechanism, swings in a recess connected with the circular cavity. This connection affords a sufficient hold for the pulling 30 action of the toggles in drawing the plates E inward toward the center of the door, and it provides an especially efficient bearing for 35 the strain in the opposite direction, that which thrusts the plates E outward into their respective grooves. The strain in the latter direction is far greater than that required to draw the plates inward. My construction, 40 forming cylindrical recesses in the plates E and providing them with wedge-shaped openings just sufficient to allow the link to swing to the required extent, makes a union which is uniform through the whole thickness of 45 the plate. It is eminently adapted to endure a very great strain, such as results both in theory and in practice when a tolerable force is applied to a toggle to urge it into the straight condition.
- 50 I attach importance to the fact that my main locking-plates E extend continuously each nearly the whole length of its respective side, with their ends oblique, as shown, and that the corner-pieces I are made wedge-55 shape, with the small ends outward, and have a greater motion than the side plates, because the continuous length of each side plate gives strength and simplicity not otherwise attainable.
- 60 Modifications may be made without departing from the principle or sacrificing the advantages of the invention. I can vary the arrangement of the connections from the wheel P to the several toggles G H. Fig. 5 65 shows such modification, there being two rods or links extending upward from the pin P', pivoted, respectively, at their upper ends to

arms on a lever, which lever performs the functions of the lever K in giving the required motion to the proper corner-piece, and 70 also connects by links to a duplicate set of toggles corresponding to G H, which give the less but strong motion to the plates E.

Instead of locking the wheel P, I can secure the safe by engaging any suitable lock or 75 locks with my mechanism at other points.

The invention has in my experiments been intended for large stationary safes, technically " vaults," which constitute portions of a building, or of the foundation therefor; but 80 I do not confine the use of the invention to such situation. It may be used in portable safes and wherever it may be required.

When the plates E are long and of only a little breadth and thickness, so as to be liable 85 to spring, I may employ additional toggles corresponding to G H, distributed equidistant along the length of each, connecting them together by links corresponding in position to the links L.

The plates E as operated constitute a rectangular expanding ring.

I claim as my invention—

1. In a vault or safe, a rectangular door-frame having a groove, in combination with 95 a door having plates, and mechanism for moving such plates outward to engage in such groove when required, such mechanism having the two sets of toggles N N and G H, acting one upon the other so as to apply a great 100 force toward the end of the outward movement, substantially as herein specified.

2. In a door for vaults or safes, having a guiding-slot or guide d extending longitudinally, the link O and operating-wheel P, with 105 locking means M therefor, said link having a pin O' for taking hold of said guide, in combination with each other and with the links N N, acting togglewise transverse to the door, and the links G H, acting to force the plates 110 E outward, the force being thereby great at the end of the movement and the motion being equal on the two sides of the door, as herein specified.

3. In a vault or safe, the wedge-shaped 115 corner-pieces I I', in combination with movable plates E, having correspondingly beveled and grooved ends, and mechanism, substantially as specified, for moving the corner-pieces outward and inward to a large extent and 120 for moving the plates E outward and inward to a smaller extent, all arranged for joint operation, substantially as herein specified.

4. In a vault or safe, the door D, oscillating wheel P, arranged to be operated from the 125 outside of the safe, links O N N, two sets of toggles G G, each rigidly connected to its mate at a right angle, as shown, and toggle-links H, engaged therewith, arranged to urge the movable plates E outward and inward at 130 the top and side of the door at the same time by a single motion, substantially as herein specified.

5. In a vault or safe, the rectangular door-

- frame B, having a groove *b*, the door D, movable plates E, matched in said groove *b*, and operating-toggles G H, with connections N O P' P for operating them, in combination with 5 each other and with corner-pieces I, link J, bell-crank lever K, and means, as the link L, for communicating the large amount of motion required, all arranged for joint operation, substantially as herein specified.
- 10 6. In a vault or safe having rectangular doors and rectangular door-frames, the links II, each having a cylindrical head H' with its axis at right angles to the link, in combina-

tion with locking-plates E, having corresponding cylindrical recesses, with openings for 15 allowing the links to swing, and with mechanism for strongly operating such links, all substantially as herein specified.

In testimony whereof I have hereunto set my hand, at Providence, this 14th day of May, 20 1890, in the presence of two subscribing witnesses.

WILLIAM CORLISS.
